UNITED STATES PATENT OFFICE.

GEOFFREY MAXWELL BOUMPHREY, OF BAYCLIFFE, LYMM, ENGLAND.

DISK-RECORD CABINET.

Application filed February 26, 1921. Serial No. 448,270.

To all whom it may concern:

Be it known that I, GEOFFREY MAXWELL BOUMPHREY, a British subject, residing at Baycliffe, Lymm, Cheshire, England, have 5 invented certain new and useful Improvements in Disk-Record Cabinets, of which the following is a specification.

This invention has for its object to provide a cabinet for gramophone or like 10 sound-reproducing machine records of the disk type wherein the disk records are stored flat but are presented for inspection in a vertical or approximately vertical position, thus ensuring freedom from warping during storage, and ease of selection and withdrawal for use. Moreover, according to the 15 invention, economy in space is effected, as it is in known constructions impracticable to store more than about a dozen records 20 flat in one pile owing to the difficulty of withdrawing the lower one.

The invention accordingly consists in a box-shaped holder rotatably mounted on trunnions or the like and preferably having 25 partitions on which the records may be piled in separate stacks.

The trunnions are preferably arranged slightly off the centre of gravity of the 30 loaded box so that the box tends to return to and be maintained in its horizontal position automatically under the action of gravity. The lid is arranged vertically and 35 is preferably so designed as to remain in a vertical or approximately vertical position during the tilting of the box, either by the provision of levers or by a gravity device. The box may be mounted directly upon a stand and be provided with a handle for 40 tilting and opening, or it may be arranged within a cabinet and adapted to be tilted automatically on raising the cabinet lid.

The invention is illustrated in the accompanying drawing in which Figs. 1 and 2 45 represent one form in which the lid is controlled by links, Fig. 3 represents a modification in which the lid is gravity-controlled, and Fig. 4 shows a third form wherein the holder is mounted within a cabinet and is automatically tilted on raising the lid.

50 Referring now to Figs. 1 and 2, the cabinet comprises a box 1 having shelves or partitions 2. It is mounted by means of trunnions 3 in a stand 4 preferably having a table-top 5. The lid 6 is seated vertically 55 against the box when the latter is in its normal position; and when the box is tilted

as shown in Fig. 2, the lid opens so as to remain vertical under the action of a hinged link 7 which is pivoted to a fixed part of the frame as shown. A spring catch 18 is 60 provided to maintain the box in the open position; this catch can be withdrawn by a button 19 to release the box. The trunnions are off-set slightly so as to cause the box to return to the position shown in Fig. 65 1 under the action of gravity, and the constraint of the lid to remain vertical serves to prevent the escape of the records if the box is allowed to fall or is returned to its normal position otherwise than gently. 70

Fig. 3 shows a modification in which the lid is maintained vertical by means of a weight 8 which in the closed position abuts against a rail 9 in the supporting stand so as to maintain the lid in the closed position 75 until the box is tilted. A spring catch 18' is also provided.

Fig. 4 shows diagrammatically a modification in which the box is pivoted within a cabinet 10 and is tilted about its trunnions 80 11 on the opening of the lid 12 by means of a link 13. In this figure it will be seen that provision has been made for two sets of records side by side.

This arrangement providing for two sets 85 of records is, of course, applicable to any embodiment of the invention.

In all forms it will be seen that the records are stored horizontally but are tilted 90 into a vertical or approximately vertical position for inspection or withdrawal, and that the lid is normally prevented from opening while the records are horizontal.

In connection with the improved cabinet it is intended that the records be either contained each in a separate envelope or separated by a loose partition. The envelope or partition may be made of light press board or other suitable material and bears, preferably on a label mounted adjacent to the top 100 edge when the cabinet is open, the title of the record. This label is preferably of a distinctive colour in order to divide the records into categories such as orchestral, vocal, etc., to each of which a colour is allotted. 105

Further, instead of tilting about a fixed axis I may arrange that the box is supported by means of rollers or wheels adapted to roll upon a horizontal or inclined bearing surface as the box is tilted. 110

I claim:—

1. In a cabinet for holding and storing

disk records for gramophones or the like, a box-like holder rotatable on a horizontal axis, a lid movably connected to the holder, and means whereby the lid may be held in a substantially vertical position in all movements of the holder.

2. In a cabinet for holding and storing disk records for gramophones, a rotatable box-like holder mounted on trunnions, the axis of the trunnions being offset from the centre of gravity of the holder so that the latter tends to return under gravity to a predetermined position, a lid movably connected to the holder, and means whereby the lid is maintained substantially vertical in all movements of the holder, the movement of the holder under gravitational influence serving to return the holder to normal position and to move the lid in closed relation to the holder thru said means.

3. In a cabinet for holding and storing

disk records for gramophones, a rotatable box-like holder mounted on trunnions, the axis of the trunnions being offset from the centre of gravity of the holder so that the latter tends to return under gravity to a predetermined position, and means for supporting said trunnions, said holder having a hinged lid constrained always to remain substantially vertical, by means of a link hinged to said lid and to a member of said supporting means.

4. In a cabinet for holding and storing disk records, a box-like holder, means for supporting said holder to permit a vertical swinging movement thereof, a lid movably connected to the holder, and means whereby the lid may be held in a substantially vertical position in all movements of the holder.

In testimony whereof I affix my signature. 40

GEOFFREY MAXWELL BOUMPHREY.
